UNITED STATES PATENT OFFICE.

HENRY HARRILD, OF SPOKANE, WASHINGTON.

DOWEL.

1,036,229.

Specification of Letters Patent. Patented Aug. 20, 1912.

Application filed January 16, 1912. Serial No. 671,412.

To all whom it may concern:

Be it known that I, HENRY HARRILD, a citizen of the United States, and a resident of Spokane, in the county of Spokane and 5 State of Washington, have invented certain new and useful Improvements in Dowels, of which the following is a specification.

This invention is an improvement in dowel construction having for an object to provide a novel construction whereby to avoid 10 the necessity of mortising and tenoning in doors, sash or other wooden frames and to provide a novel construction for holding together any wooden joint; and the invention 15 consists in certain novel constructions and combinations of parts as will be hereinafter described and claimed.

In the drawing Figure 1 is a side view of the dowel ready for use, and Fig. 2 is a 20 similar view of the dowel applied for use.

In the accompanying illustration I present a form of dowel adapted for use in the making of small frames or joints. In this construction, the dowel has a center piece 2 which projects beyond the side spurs 1, so 25 that a hammer can be used to strike upon the center piece and drive the dowel without injury to the sharp points or spurs on opposite sides of the said center piece.

I claim:

30 A dowel split from its end forming side spurs and a central portion which projects at its end beyond the ends of the side spurs.

HENRY HARRILD.
